UNITED STATES PATENT OFFICE.

OTTO E. J. SEITZ, OF NEW YORK, N. Y., ASSIGNOR, BY DIRECT AND MESNE ASSIGNMENTS, OF ONE-HALF TO ARTHE, LEVY, BERNHARD COMPANY, OF NEW YORK, N. Y., A CORPORATION OF NEW YORK, AND ONE-HALF TO SUPLEE, REEVE, WHITING COMPANY, OF PHILADELPHIA, PENNSYLVANIA, A CORPORATION OF NEW JERSEY.

DESIGN FOR A PARASOL.

46,701.

Specification for Design.

Patented Nov. 24, 1914.

Application filed August 20, 1912. Serial No. 716,106. Term of patent 14 years.

To all whom it may concern:

Be it known that I, OTTO E. J. SEITZ, a citizen of the United States, residing at the city of New York, in the State of New York, have invented a new, original, and ornamental Design for Parasols, of which the following is a specification, reference being had to the accompanying drawing, forming part thereof.

The figure is a side elevation of the parasol opened.

I claim:

The ornamental design for a parasol as shown.

OTTO E. J. SEITZ.

Witnesses:

I. H. BERNHARD,

FRANK W. LEVY.
